DONALD H. BUSHEY, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

ELECTRICAL DETECTOR MECHANISM FOR DROP BOX LOOMS

Application filed April 16, 1931. Serial No. 530,619.

This invention relates to improvements in electrical weft detectors for drop box looms and it is the general object of the invention to provide such a mechanism wherein the indication can be given prior to the completion of the movement of the boxes as they shift.

In certain classes of looms employing two shuttles which are active alternately so that each is running for two picks and is then idle for two picks and wherein a weft detector for each shuttle is employed, the indication of weft exhaustion cannot be taken directly from the feelers because both may indicate at the same time. In view of the fact that when the lay is at front center one shuttle is moving into action and the other out of action, it becomes necessary to select which detector shall control the loom so that the one corresponding to the shuttle which will next be active may call for a change if this be desirable. Accordingly, it is an important object of my present invention to provide a circuit closer which shall determine early in the shifting movement of the boxes which of two circuits can be closed if weft exhaustion exists in the shuttle next to be active.

It is a further object of my present invention to provide a mechanical switch which shall be operative by movement in one direction to close one electric switch and operative by movement in the opposite direction to close another switch. Ordinarily the boxes are supported by a box lifter rod which rises and falls and I employ this movement in connection with the mechanical switch to call into action a contact corresponding to the shuttle next to be active.

With these and other objects in view which will appear as the description proceeds, my invention resides in the combination and arrangement of parts hereinafter described and set forth in the claims.

In the accompanying drawings, wherein a convenient embodiment of my invention is set forth,

Fig. 1 is an end elevation of a loom having my invention applied thereto,

Fig. 2 is an enlarged end elevation of a portion of the structure shown in Fig. 1, illustrating the mechanical switch,

Fig. 3 is a vertical section on line 3—3 of Fig. 2,

Fig. 4 is an enlarged side elevation of a detail of the mechanical switch,

Fig. 5 is a detail front elevation on an enlarged scale taken in the direction of arrow 5, Fig. 2,

Fig. 6 is an enlarged horizontal section taken on line 6—6 of Fig. 2,

Fig. 7 is an enlarged horizontal section on line 7—7 of Fig. 1,

Fig. 8 is a top plan view of one of the detectors, and

Fig. 9 is a diagrammatic view of the circuits employed.

Referring to Fig. 1, I have shown a loom frame 10 having a lay 11 supporting a gang of shifting boxes 12. Upper and lower boxes 13 and 14, respectively, may house upper and lower shuttles 15 and 16. The gang of boxes is supported on a lifter rod 17 which may be attached at the lower end thereof to a box lifter lever 18 moved by any approved box motion not shown herein. The boxes are controlled by the lever so that they are active for two picks and then idle for two picks.

The detector mechanism comprises a frame 20 secured to the loomside and having a guide 21 to receive a slide 22. The latter is provided with upper and lower platforms 23 and 24, respectively, on which are located electrical weft detectors 25 and 26, respectively. A rod 27 is pivotally connected to the lower end of the slide 22 and also has operative connection with the lever 18 so that the detectors move vertically with the boxes, the detectors always registering with their respective boxes.

Each detector may be of the type shown in Fig. 8 and comprises a bed 30 formed of insulating material which may be held by screws 31 to the corresponding platform. Detector fingers 32 and 33 for each bed may slide toward and from the corresponding shuttle against the action of springs 34. The latter normally hold the detector fingers yieldingly in rear position. The detector finger 32 may have a clip 35 while the other finger 33 may be connected to a clip 36.

It is to be understood that when exhaustion

in either shuttle occurs the pair of detector fingers 32 and 33 corresponding thereto will be electrically connected by well-known means which need not be described here. It is sufficient to state that when exhaustion in either shuttle occurs the clips 35 and 36 corresponding to such shuttles will be in electrical contact with each other. The matter thus far described of itself forms no part of my present invention and is given for the purposes of illustrating one means of carrying my invention into effect.

My present invention relates more particularly to selecting means for determining which of two circuits shall be closed if exhaustion is present in the weft moving into action, and in carrying my invention into effect I secure an arm 40 to the lifter rod 27 by a set screw 41 and pivotally connect to said arm a rod 42. The latter may extend through a housing 43 secured by means of bolts 44 to the loom frame. The rod 42 has extending therefrom an actuator finger 45. The housing is provided with slide bearings 46 through which the rod 42 reciprocates as the boxes rise and fall.

As shown more particularly in Fig. 3, the housing is provided with a vertical wall 47 to which is secured a stud 48 by means of a nut 49. The stud has a head 50 between which and the wall is located a bearing 51 of a lever 52. The latter is free to swing around the stud 50, but is restrained as to motion by means of springs 53 and 54 which are respectively to the right and left of the lug 55 on the lever as shown in Fig. 2. These springs may surround a guide rod 56 which passes through the lug and said springs are substantially equal so that they maintain the lever ordinarily in the intermediate position shown in Fig. 2.

Side wall 57 of the housing carries an insulated spring contact 58 which is connected to a wire 59, while the opposite side wall 60 is similarly provided with a spring contact 61 which is connected to a wire 62. The spring contacts 58 and 61 are insulated from their respective supporting walls and the lower end of the lever 52 is proportioned to have contact with one or the other of these spring contacts at a time, depending upon its angular position relatively to the rod 42. As a matter of convenience the lever 52 is electrically grounded to the loom frame.

Fig. 6 shows a detail of one of the spring contacts, namely, that shown at the left of Fig. 2. The contact spring 61 is held by the head 63 of the screw 64 against an insulating bushing 65. An insulating washer 66 located on the outside of the wall 60 receives the thrust of a nut 67 on the screw 64 and also positions the wire 62. It is to be understood that the spring contact on the right hand wall is similar in construction and electrical

relation with respect to the housing to that shown in Fig. 6.

The lever 52 as shown herein is provided with a guide lug 70 having right and left hand vertical walls 71 and 72, respectively, the right hand wall being curved at the upper end thereof to the left, as at 73, to meet the wall 72, and the latter at the lower part thereof being curved to the right, as at 74, to meet the right hand vertical wall. The lug 70 may be located in a recess 75 into which the actuator 45 projects. The maximum vertical dimension of the lug 70 is preferably slightly less than the amount of motion of the rod 42 induced by shifting of the shuttle boxes.

In operation, assuming that the parts are in the position shown in Figs. 3 and 4, the actuator finger 45 will be located substantially centrally between the vertical walls 71 and 72 under the surface 74. Under these conditions the boxes will be in their lower position and as they start to rise the cam surface 74 will be moved to the right to cause the lever 52 to swing from the full to the dotted line position shown in Fig. 2. After the finger reaches the vertical wall 72 further angular movement of the lever will be substantially eliminated. When moved to the dotted line position shown in Fig. 2 the lever will have contact with the right hand spring 58, and the latter will yield to accommodate any further angular movement induced by continued upward movement of the finger 45.

It is to be understood that the lay will reach its front position with the detectors operative to determine the condition of weft in both shuttles at a point in the cycle of the loom when the actuator finger will be at a point intermediate the cams 73 and 74. As the boxes continue to move upwardly, thereby moving the lower box to active position, a time will come when the top of the surface 72 will pass under the actuator finger 45, thereby freeing the lever 42 so that the spring 53 may return said lever to the intermediate position shown in full lines in Fig. 2.

When the lever is moved to the dotted line position shown in Fig. 2 due to upward movement of the boxes, the following circuit will be closed, reference being had to Fig. 9: source of electric power P, wire 80, clip 35 of the upper feeler, corresponding fingers 32 and 33, upper clip 36, wire 59, contact spring 58, arm 52, wire 81 to the ground, from the ground over wire 82, solenoid or other electromagnetic device E, and wire 83 back to the source of electric power. Current flowing in this circuit will energize the solenoid E and the latter will attract its armature 84 to effect a change in the operation of the loom when the shuttle corresponding to the lower box is on the single box side of the loom, or that side opposite to the end shown in Fig. 1. In view of the fact that lever 52 under the as-

sumed conditions is moved away from spring contact 61 which corresponds to the upper shuttle, the loom will operate independent of the condition of weft in said upper shuttle, the lower shuttle alone being in control of the loom.

If, on the other hand, the weft in the top shuttle should at some subsequent pick become exhausted just prior to the time that 10 said shuttle is to move back into action, the boxes will move down to place the top cell 15 in picking position. Downward movement of the boxes will be accompanied by a similar movement of rod 42, so that the actuator finger 45 will move over the face 73 and cause the latter to move to the left, holding lever 52 in contact with spring 61 during the time that the detectors are in engagement with the weft. Under this second assumed condition, current will flow through 20 the following circuit: electric source of power P, wire 80, clip 35 of the lower shuttle, feeler fingers 32 and 33 of the lower shuttle, clip 36 of the corresponding shuttle, wire 62, contact spring 61, lever 52, wire 81, ground, wire 82, solenoid E, and wire 83 back to the battery. Current flowing in this circuit will energize a solenoid E to bring about the same results as those which existed when the first 30 circuit traced was completed.

It is to be understood that closing of either of the circuits hereinbefore described will energize the solenoid with resultant change in the operation of the loom, as stoppage or 35 replenishment, but the parts are so related that the shuttle which is moving into action determines which contact will be closed, and what is equally important, the shuttle which is moving toward, or is already in idle position, will have no opportunity to close its circuit until it again moves toward active position. In this way the loom is controlled only by the shuttle which closes this circuit, that is, the shuttle which needs replenishment.

45 The lower part of Fig. 9 sets forth structure additional to that which has already been described to effect a change in the loom. A vertically reciprocating actuator 90 normally clears a controller pin 91 on the armature 84 because the latter is held to the left by a light spring 92. When the solenoid is energized, however, the pin 91 will move under the actuator and the latter will be timed to descend when the circuits are closed, so as to have 50 its movement interrupted by the controller 91 to bring about a change in the loom. This method of controlling the loom is similar to that which exists in multicolor weft replenishing looms, but is set forth herein merely as one means of accomplishing a change in the operation of the loom when weft exhaustion exists in the shuttle about to become active. It is to be understood that my invention is not limited to the use of the form of 55 weft detector shown in Fig. 8, as the device

set forth herein to select which of the two circuits shall be operative will be effective with any type of weft detector which acts to make a contact while the boxes are shifting and at the time of weft exhaustion.

70 From the foregoing it will be seen that I have provided means dependent upon the movement of the boxes to operate a circuit selector the effect of which is to permit the closing of a circuit corresponding to the shuttle which is moving into action. The device operates preferably so as to make its selection not later than the engagement of the weft detectors with their wefts. In this connection it is to be understood that the feelers do not engage their bobbins as soon as the shuttles are boxed but have such contact for a relatively short time only intermediate the beginning and the ending of the box shift at the time the lay is in its foremost position. 80 It will also be seen that even though this latter condition should not exist and the circuit through the shuttle could be established as soon as the shuttle is boxed, the corresponding circuit nevertheless would not be 85 closed because the lever 52 is normally in the intermediate position shown in full lines in Fig. 2 where it is out of contact with both the springs 58 and 61.

90 Having thus described my invention it will 95 be seen that changes and modifications may be made therein by those skilled in the art without departing from the spirit and scope of the invention and I do not wish to be limited to the details herein disclosed, but what 100 I claim is:

1. In a drop box loom having a pair of shuttle boxes each moved by a box lifter rod to active position for two successive picks and then inactive for two picks, an electromagnetic device to cause a change in the operation of the loom, a pair of electric detecting circuits to which the device is common, an electric weft detector for each box, one detector for each circuit, and a selector to determine which circuit shall be operative, said selector comprising a pair of coacting members one of which is connected to the box rod and movable with the boxes in the direction in which the latter shift and the other of which is movable by the first in the direction transverse of the lifter rod, and a pair of contacts, one for each detector circuit, to be engaged one at a time by one of the members, the contact which is engaged by the member being dependent upon the direction of movement of the boxes.

110 2. In a drop box loom having a pair of shuttle boxes each in active position for two successive picks and then inactive for two picks, an electromagnetic device to cause a change in the operation of the loom, a pair of electric detecting circuits to which the device is common, an electric weft detector for each box, one detector for each circuit,

- and a selector to determine which circuit shall be operative, said selector comprising a reciprocating actuator movable with the boxes, a pair of contacts one for each detector circuit, and a contact engaging member to have engagement with one of the contacts at a time, said member being moved by the actuator and having two cam faces, one to be engaged when the actuator moves in one direction to cause engagement with one of the contacts, and the other cam face to engage the actuator when the latter moves in the opposite direction to cause engagement of the member with the other contact.
3. In a drop box loom having a pair of shuttle boxes each in active position for two successive picks and then inactive for two picks, an electromagnetic device to cause a change in the operation of the loom, a pair of electric detecting circuits to which the device is common, an electric weft detector for each box, one detector for each circuit, and a selector to determine which circuit shall be operative, said selector comprising an actuator movable with the boxes in a substantially fixed line of motion, a pair of electric contacts, one for each detector circuit, and a member movable from one contact to the other by a force derived from the actuator, said member having inclined faces which normally lie on both sides of the path of movement of the actuator, the latter when moving in one direction engaging one face to move the member into engagement with one contact, and said actuator when moved in the opposite direction to engage the other face to move the member into engagement with the other contact.
4. In a drop box loom having a pair of shuttle boxes each in active position for two successive picks and then inactive for two picks, an electromagnetic device to cause a change in the operation of the loom, a pair of electric detecting circuits to which the device is common, an electric weft detector for each box, one detector for each circuit, and a selector to determine which circuit shall be operative, said selector comprising an actuator movable with the boxes in a fixed path, a pair of contacts one for each detector circuit, a member movable between the contacts to engage one contact at a time, a pair of oppositely inclined cam faces on the members, means to hold the member yieldingly in intermediate position with the inclines extending on opposite sides of the line of action of the actuator, movement of the latter in one direction engaging one of the faces to move the member against one of the contacts, and the actuator when moving in the other direction engaging the other inclined face to move the member against the other contact.

In testimony whereof I have hereunto affixed my signature.
